Primary Examiner — Cynthia Ramirez*Assistant Examiner* — Jeremy S. Swartz(74) *Attorney, Agent, or Firm* — Faegre Drinker Biddle & Reath LLP(57) **CLAIM**

The ornamental design for a filing pedestal, as shown and described.

DESCRIPTION

FIG. 1 is an isometric view of a filing pedestal illustrating our new design in a closed configuration.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is an isometric view of the filing pedestal in an open configuration; and,

FIG. 9 is a right side view thereof.

Features of the filing pedestal shown as broken lines form no part of the claimed design.

1 Claim, 7 Drawing Sheets(56)
